of Delaware

Application April 16, 1953, Serial No. 24,540

Term of patent 14 years

(Cl. D86—10)

To all whom it may concern:

Be it known that I, Frederick M. Breen, a citizen of the United States, residing at Westchester, in the county of Westchester and State of New York, have invented a new, original, and ornamental Design for a Combined Lipstick Holder and Vanity Case or Similar Article, of which the following is a specification, reference being had to the accompanying drawing, forming part thereof.

In the drawing:

Fig. 1 is a top plan view of a combined lipstick holder and vanity case or similar article, showing my new design;

The dominant features of my design reside in the portions shown in full lines.

I claim:

The ornamental design for a combined lipstick holder and vanity case or similar article, substantially as shown and described.

FREDERICK M. BREEN.
